CLAIM

The ornamental design for a display screen or portion thereof with graphical user interface, as shown and described.

DESCRIPTION

FIG. 1 is a front view of the first image in the sequence for our new display screen or portion thereof with graphical user interface design;

FIG. 2 is a front view of the second image in the sequence for our new display screen or portion thereof with graphical user interface design; and,

FIG. 3 is a front view of a third image in the sequence for our new display screen or portion thereof with graphical user interface design.

The appearance of the transitional image sequentially transitions between the images shown in FIGS. 1-3. The process or period in which one image transitions to another image forms no part of the claimed design.

The outermost broken line in the figures illustrates a portion of a display screen that forms no part of the claimed design. Similarly, the remaining broken lines represent features of the graphical user interface that form no part of the claimed design.
